J. O. TOW,
INTERNAL COMBUSTION ENGINE CYLINDER
APPLICATION FILED APR. 24, 1917.

1,273,109.

Patented July 16, 1918.

INVENTOR.

James O. Tow.

UNITED STATES PATENT OFFICE.

JAMES O. TOW, OF COLUMBIA, MISSOURI.

INTERNAL-COMBUSTION-ENGINE CYLINDER.

1,273,109.

Specification of Letters Patent. Patented July 16, 1918.

Application filed April 24, 1917. Serial No. 164,088.

To all whom it may concern:

Be it known that I, JAMES O. Tow, a citizen of the United States, residing at Columbia, in the county of Boone and State 5 of Missouri, have invented a new and useful Internal-Combustion-Engine Cylinder, of which the following is a specification.

My invention relates to improvements in internal combustion engine cylinders in 10 which liquid or other fuel is drawn into or forced into a cylinder provided with a piston and valve or valves, for combustion with air which is also drawn or forced into said cylinder; and the objects of my improvement are, to provide a practical and 15 efficient internal insulation for that part of the cylinder which is exposed to the fire, so as to prevent heat loss; and to simplify construction.

20 I attain these objects by the construction illustrated in the accompanying drawing in which a vertical section of the cylinder is shown complete with piston.

The metal shell, 1, is made with two diameters and the larger end, which is also the head end, is lined for a distance as shown, the lining extending to the piston head when the piston is at the end of the first or third stroke in the case of a four 25 cycle cylinder.

The insulation is coned off toward the head.

The insulation, 3, is built up from rings of mica, asbestos, or other heat insulation 35 material, alternating with relatively thin rings of metal for support and protection.

The piston, 2, is made with two diameters, the lower or larger part fitting the lower metal faced bore of cylinder, the 40 smaller part of piston operating within both the metal faced and insulated parts of bore but in contact with neither part of cylinder as shown.

The opening, 4, in the cylinder head is

for the use of valve, valves or valve assembly, and for the spark plug when jump spark ignition is used. The pitman is shown at 5, and the piston head insulation at 6. A ring, 7, may be used to retain the piston head insulation.

At 8, is shown a small hole into which may be inserted a small auxiliary air valve if desired, to help cool the upper part of piston. Several of these holes may be provided around the cylinder if desired.

The above special insulation construction which is my invention may be employed in two cycle, four cycle, Diesel or semi-Diesel cycle motors.

I am aware that insulations for internal combustion engine cylinders have been invented and patented by others and that pistons having clearance with such insulations have been used. Therefore I do not make broad claims covering the use of every kind of insulation with a cylinder and a piston with clearance, but limit my claims to the special insulation construction with a cylinder shell and piston substantially as described.

70 Therefore I claim:

1. In an internal combustion engine cylinder, the combination with a metal cylinder wall of an insulation lining built up of rings of insulating material alternating 75 with metal rings.

2. The combination, in an internal combustion engine cylinder of a metal cylinder shell of two diameters, a lining for the part of larger diameter composed of rings of insulating material alternating with rings of metal, together with a piston of two diameters, the larger part of said piston fitting and operating within the metal part of cylinder bore, the smaller part clearing 80 but operating within the insulated part of cylinder and metal part as well.

JAMES O. TOW.
